UNITED STATES PATENT OFFICE

WILLIAM B. CHAPMAN, OF JACKSON HEIGHTS, NEW YORK, ASSIGNOR TO THE CHAPMAN-STEIN FURNACE CO., OF MOUNT VERNON, OHIO, A CORPORATION OF OHIO

RECUPERATOR

Application filed June 26, 1926. Serial No. 118,782.

The invention aims to provide a recuperator which shall occupy less space, cost less and be less likely to leak or require repairs, and be more efficient than recuperators now 5 in general use.

One object of the invention is to so arrange the passageways within the recuperator between which heat interchange is to take place, that the area available for such heat interchange will be relatively large as compared 10 to the volume of the recuperator.

Another object is to provide a construction in which, to a large extent, the radiation losses, due to travel of the gases past exposed 15 or non-heat interchanging surfaces of the recuperator, will be avoided.

From the structural standpoint, the invention also aims to provide a recuperator made up of simple elements, requiring a 20 minimum of special shapes of tile or other parts.

Further objects and advantages of the invention will be in part obvious and in part 25 particularly pointed out in the description hereinafter contained which, taken in conjunction with the accompanying drawings, discloses certain preferred embodiments thereof. Such embodiments, however, should be considered as merely illustrative 30 of its principles. In the drawings—

Fig. 1 is a central longitudinal sectional view of the recuperator constructed in accordance with the invention, the section being taken on line 1—1 of Fig. 2.

Fig. 2 is a stepped transverse section of the recuperator shown in Fig. 1, the section being taken approximately on line 2—2 of Fig. 1.

Fig. 3 is a detail longitudinal section showing enlarged adjacent sets of tiles such as may be employed in the recuperator shown in Fig. 1.

Fig. 4 is a perspective view showing one 45 of such tiles described.

Fig. 5 is a perspective view showing detached a baffle cap such as may be employed as a part of the recuperator shown in Fig. 1.

Fig. 6 is a transverse sectional view of 50 another form of recuperator, constructed in

accordance with the invention, the section being taken on line 6—6 of Fig. 7.

Fig. 7 is a central longitudinal section of the recuperator shown in Fig. 6.

Fig. 8 is a view similar to Fig. 1 but showing a modified form of recuperator.

Recuperators are of two general types, first, those designed for the air to be heated to be forced through them by artificial draft and, second, those in which the air flows 60 through by natural draft. The present invention is applicable to both types of recuperators.

In accordance with one feature of the invention the recuperator is provided with two 65 series of passageways disposed transversely to each other, the partitions forming such passageways being so constructed that the gases in following a sinuous path through one series of passageways, turn alternately 70 in the central portion of the recuperator and near the outer walls thereof. Thus the gases, while turning in the central portion of the recuperator, are in good thermal relation to the heat transfer surfaces of the recuperator, 75 avoiding radiation losses which occur when the gases make exterior turns in passing through the recuperator.

Fig. 1, for example, shows a recuperator of the forced draft type, the air to be heated 80 being fed in through a pipe 1 to a distributing chamber 2 disposed at the top of the recuperator outer walls 3 and provided with a suitable number of holes 4 leading to the interior of the recuperator. The pipe 1 preferably is tangential to chamber 2, thereby producing a whirl of air around the chamber and causing even flow of air through the recuperator. The exhaust gases which supply the heat are led into the recuperator through 85 one or more flues 5 leading to a chamber 6 located in the base 7 of the recuperator, the flues 5 being also preferably directed tangentially to chamber 6, to obtain even distribution of the exhaust gases.

One series of passageways is provided with a plurality of parallel columns each made up of hollow tiles 8. In the present instance the head of each tile is provided with a seat 9 (Fig. 3) upon which rests the bottom of the 90 100

tile next above. I prefer to build the tiles in the simple cylindrical shape illustrated and they may be made of metal or refractory material, according to the conditions of use.

5 In the present instance the hollow tiles 8 partition off the interior of the recuperator to form a plurality of vertical passageways 9 which accommodate the exhaust gases, such passageways being connected to the chamber 6 through openings 10 in the base of the recuperator and delivering the exhaust gases, after they have given up their heat, to a gathering chamber 11, located at the top of the recuperator.

15 The hollow tile columns above mentioned are so disposed within the outer walls 3 of the recuperator as to leave spaces in the central portion of the recuperator, and near its outer walls, through which the gases surrounding the tiles may pass, and partitions transverse to such tiles are provided, which divide the spaces within the recuperator and exterior to the tiles, into a second series of parallel passageways 12 transverse to and 20 enclosing the passageways 9 above mentioned.

25 As shown in Fig. 1, these transverse partitions are made up in the main of interfitting flanges 13 on the heads of adjacent tiles of adjacent columns, a construction which I prefer since it reduces the number of special parts necessary to be used in building the recuperator and also reduces the weight. The hexagonal shape of recuperator, as shown in Fig. 2, is also preferred since it enables 30 the adjacent columns of tiles to be set relatively close to each other, thus making the recuperator more compact. The shape of the tile flanges also preferably conforms to that of the outer walls. The flanges 13 of the 35 tiles are also preferably provided with beveled sides 14 (Figs. 3 and 4), and match together fairly loosely, whereby each column may move longitudinally independently of the others; this construction permits unequal 40 longitudinal expansion and contraction to take place without disturbing tiles of adjacent columns or loosening up of the joints between the air and exhaust gas passageways, and without causing substantial leakage between adjacent passageways 12. The beveled sides 14 of the tile facilitate such trimming as may be necessary in building the recuperator and form receptacles between the assembled tiles, which collect dust and thereby seal 45 the joints.

50 In the form of recuperator illustrated in Fig. 1, the air to be heated passes inwardly from inlet chamber 2 through the upper transverse passageway 12 to the center of 55 the recuperator where the transverse partition is omitted to provide an opening 16 communicating with the transverse passageway 12 next beneath. The blocks or brace members 17 extending inwardly from the outer walls of the recuperator, engage the adjacent

flanges 13 of the tiles to divide off the outer portion of the upper passageway 12, whereby the only exit from this passageway is through opening 16 above mentioned.

50 The air to be heated next passes outwardly from the central portion of the second passageway 12 toward the outer walls of the recuperator, the central portion of the partition beneath this passageway being closed off as by means of a suitable cap 18. The 55 blocks or brace members 17^a associated with the partition underneath the second passageway 12 are similar to the blocks 17 above described, except that openings 19 are provided therein which permit the air when it reaches the outer portion of the second passageway 12 to turn downwardly and pass into the third passageway 12 next beneath. Adjacent passageways 12 are thus provided alternately with central openings 16 and outer openings 19 adjacent the outer walls 3 of the recuperator, whereby the air to be heated passes through the recuperator in a sinuous path, traveling alternately out from, and toward the central portion of the recuperator. From the bottom chamber 12 the heated air passes into an annular gathering chamber 20 from which it may be led off through one or more suitable flues 21.

55 It will be understood that if desired the exhaust gases may be led through passageways 12 and the air to be heated through passageways 9, if desired, also that the direction of flow may be reversed.

60 The embodiment of the invention illustrated in Figs. 6 and 7 is similar to the recuperator above described, except that the flanges 13^a of the tiles support separate partition members 22 which may be in the form of sector-like parts, as shown in Fig. 6, and 65 suitably shaped to accommodate the tiles.

65 In Fig. 8, I have illustrated a recuperator of the natural draft type which is similar to the one described in Figs. 6 and 7, except that the exhaust gases enter the tiles 8 from a distributing chamber 23 located at the top of the recuperator and pass downwardly to a gathering chamber 24 located in its base. The air to be preheated enters the bottom transversely of passageway 12 through an 70 annular distributing chamber 25 having openings 26 in its inner wall and passes upwardly through the several passageways 12, as above described, to an annular gathering chamber 26 located at the top of the recuperator. When this type of recuperator is located below the level of the furnace it feeds no fan is required for the air, but a stack or other means is required to draw the spent 75 gases downward.

75 In Figs. 7 and 8, the tile columns which would appear in the background, are omitted for the sake of simplicity.

80 The recuperator is free to expand and contract in a vertical direction due to the fact

that the tile columns are not bonded to the outer walls; in other words, the outer tile flanges for the partition members may slide along the brace members 17 and 17^a. The joints in the recuperator which should be gas-tight furthermore are all horizontal whereby the weight of the material above exerts pressure on the joints which assists in keeping them tight. The joints are also practically independent of each other whereby variations and dimensions of the tiles within manufacturing limits, do not require special fitting operations in building the recuperator or cause leaky joints.

15 The outer wall 3 of the recuperator and its surrounding shell 27 are preferably both constructed in sections, whereby in building the recuperator the interior parts may be assembled progressively up to different levels as 20 the shell sections 27 are installed. As shown, the shell sections 27 are bolted together at their flanges 28 to permit them to be detached when desired.

25 While certain specific embodiments of the invention have been described, it is obvious that many changes may be made therein without departing from the spirit of the invention, as defined in the following claims.

I claim:

30 1. A recuperator having outer walls, a series of upstanding parallel hollow tile columns therewith forming one series of passageways, adjacent tiles of said columns having flanges matching to form partitions transverse to said columns, said flanges having sides shaped to form sealing receptacles.

2. A hollow recuperator tile having a hexagonal lateral flange projecting therefrom shaped to match together with similar flanges to form a transverse partition, said flange having beveled sides.

3. A recuperator having outer walls, a series of parallel hollow tile columns therewith forming one series of passageways, brace members extending from said walls to the outer tiles of said columns at different levels which brace members alternately open and close communication between the opposite sides thereof.

45 4. A recuperator having outer walls, a series of upstanding parallel hollow tile columns therewithin, adjacent tiles having hexagonal flanges extending therefrom to provide lateral bracing for said columns, the outer walls conforming in shape to the cross section of the flanges.

50 5. A recuperator having outer walls, a series of parallel hollow tile columns therewithin forming one set of passageways, adjacent tiles of adjacent columns having flanges matching to form partitions transverse to said columns, said flanges having beveled edges to provide receptacles between adjacent flanges.

55 6. A recuperator having outer walls, par-

70 tition members therewithin forming one series of parallel passageways running through the recuperator and a second series of passageways running transverse to the first series, adjacent passageways of said second mentioned series being connected alternately in the central portion of the recuperator, and near the outer walls thereof, together with chambers at the opposite ends of the recuperator communicating respectively with said series of passageways, and means for setting up a whirling motion of gases entering said chambers to distribute the gases evenly between the corresponding passageways.

75 7. A recuperator having a distributing chamber, a series of passageways communicating therewith, and means for causing a whirling motion of the gases in said distributing chamber to apportion the same evenly between said passageways.

80 8. The combination of claim 4, wherein said flanges also form a series of passageways running transverse to the passageways within the hollow tile columns, said transverse series of passageways being connected alternately at the central portion of the recuperator, and near the outer walls thereof.

85 9. The combination of claim 3 together with partitions transverse to the hollow tile columns, which partitions define passageways alternately connected and closed off by the brace members, the passageways which are closed off from each other by the brace members being connected at the central portion of the recuperator.

90 10. The combination of claim 3 wherein the tiles of adjacent columns are provided with flanges matching to form partitions extending transversely of the columns and thereby providing a second series of passageways transverse to the passageways within the columns, and said brace members bearing against the flanges of said outer tiles, the transverse passageways which are closed off from each other by the brace members being connected in the central portion of the recuperator.

105 In testimony that I claim the foregoing, I have hereunto set my hand this 18th day of June, 1926.

110 WILLIAM B. CHAPMAN.
